Owen, Owen & Parrott.

UNITED STATES PATENT OFFICE.

JOHN A. MAYER, OF TOLEDO, OHIO.

SILENCER.

1,182,098.

Specification of Letters Patent.

Patented May 9, 1916.

Application filed June 24, 1915. Serial No. 36,103.

To all whom it may concern:

Be it known that I, JOHN A. MAYER, a citizen of the United States, and a resident of Toledo, in the county of Lucas and State 5 of Ohio, have invented a certain new and useful Silencer; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to silencers, and it has for its object to prevent the explosive detonating pulsating sound which occurs in the operation of an unmuffled internal combustion engine.

20 The object of the invention is to produce a substantially constant outflow of the exhaust gases giving opportunity for a certain amount of expansion and at the same time to prevent the loud pulsating sound which 25 occurs in the operation of an internal combustion engine, and yet avoid all back pressure on the engine, producing a substantially constant outflow of exhaust gases.

The invention also has for its object to 30 produce an efficient silencer which may be used in connection with automobiles found generally in use and which may be easily made.

The invention may be contained in many 35 forms of construction usable for different purposes all of which come within the purview of my claims hereinafter appended. To show the practicability of my invention I have selected one of such construction as 40 an example and shall describe it hereinafter. The construction selected for purpose of illustration is illustrated in the drawings wherein—

Figure 1 is a vertical sectional view 45 through the muffler, a part thereof being shown in perspective. Fig. 2 is a sectional view through a drum located at the end of the silencer looking in the direction of the arrows 2, 2. Fig. 3 is also a section of the 50 drum looking in the direction of the arrows 3, 3. Fig. 4 is an end view of the silencer disconnected from the exhaust manifold of the engine.

1, Fig. 1, is a pipe which is connected to 55 the exhaust 2 which leads from the exhaust manifold of an automobile engine. This is

usually located beneath the automobile car and conducts the exhaust gases to the rear end of the automobile. It may be provided with a flanged collar 3 to which it is threaded. By means of the flanged collar 3 and bolts 4 connection is made with the exhaust 60 pipe 2. A strip of sheet metal 10 is placed within the pipe 1. The strip of metal is provided with a plurality of semi-circular or semi-elliptically cut tongues 11, which are located in spaced relation with respect to each other and are alternately bent to opposite sides of the strips 10. The edges of the tongues 11, as shown in Fig. 3, whether semi-circular 65 or semi-elliptical, fit the wall of the inclosing pipe, particularly at the exhaust end of the pipe. The openings 12 formed by bending the tongues from the strip are semi-circular or semi-elliptical, according to the shape 70 of the tongues. Exhaust gases pass through the openings 12, as they are directed back and forth through the strip by the tongue 11 into the short semi-cylindrical chambers which are defined by the wall of the pipe 75 and the tongues, which more or less fit the wall of the pipe. The semi-circular or semi-elliptical tongues are preferably bent away from the inlet end of the pipe, the openings 80 thus being formed in the strip at the ends 85 of the short semi-cylindrical chambers toward the exhaust end of the pipe. The tongues 11 may be slightly curved, as is best shown in the top view of the tongue 11 located at the right end of Fig. 1, to gradually 85 change the direction of the gases to the openings 12 in succession. The strip 10 is also provided with turned edges or flanges 15, which form a strengthening means for the strip 10 and moreover permit the cuts, which 90 are made to form the tongues 11, to extend to near opposite sides of the pipe, that is, to the corners formed by the flanges 15 and the body of the strip 10. If the tongues are cut along the line of a semi-circle, they may be 100 bent substantially 90° to opposite sides of the strip, so that their edges will fit the wall of the pipe. If they are cut along the line of a semi-ellipse of considerable length relative to the height, the tongues may be bent 105 so as to be located at an angle less than 90°, according to their length, to close as much as may be desired the portion of the bore or passage-way of the pipe located on the sides of the strip 10. They may also be 110 slightly curved so as to gradually change the direction of movement of the gases to

and through the openings in succession. The number of tongues formed in the strip vary according to the length and the size of the pipe.

5 The strip 10 may be secured, if desired, in any convenient way within the pipe 1. Ordinarily the fitting of the strip 10 will be sufficient to hold the strip within the pipe 1. The strip 10 may be bent spirally so that 10 one end of the strip will be located at right angles to the plane of the other end of the strip. This operates the same as giving additional length to the pipe and strip and providing additional openings and tongues. 15 When the exhaust takes place the gases will be deflected back and forth to opposite sides of the strip 10 within the pipe 1 until it finally passes out through the end of the pipe 1. At the inlet end of the pipe, a part 20 or all the gases will enter the first short chamber on one side of the strip, depending on how closely the tongue on the opposite side of the strip fits the pipe. If it does not fit the pipe, some will also enter the first chamber on the opposite side of the strip. Exhaust gases will then be directed back and forth in the pipe. As the pulsations decrease in their intensity, the gases flow in 25 the sinuous path provided for by the tongues and openings. The end of the pipe 1 may also be provided with a lens-shaped drum 20 which may be secured to the end of the pipe by means of a collar 21 which may be, if desired, spot welded to the pipe 1, or 30 may be threaded onto the pipe. I, however, have shown in the drawing a bracket 22 which operates to hold the rear end of the pipe 1 and also the drum 20 in position. The bracket 22 is suitably riveted or spot welded 35 to the side of the drum, as indicated, and may be fastened to the frame of the car as may be desired. The collar 21 fits over the end of the pipe 1.

The lower edge of the lens-shaped drum 40 20 may be provided with an elliptical opening 25. A short delivery pipe 26 is preferably secured to the drum 20 so as to receive the exhaust gases from the drum 20 and direct them diagonally downward to the rear of the 45 car. The lower end of the pipe 26 terminates in a circular port or opening 27 through which the exhaust gases are finally delivered.

The construction selected and described 50 may be greatly varied in the arrangement and manufacture of its parts and in the substitution of elements having equivalent functions, and such modifications may be used for many varied purposes and still contain the invention.

60 Having thus described my invention, what I claim as new, and desire to secure by Letters Patent, is,—

1. An engine silencer comprising a pipe 65 connected with the exhaust of an internal combustion engine and having a strip, the

strip having tongues bent alternately to opposite sides of the strip and located the length of the pipe, the strip bent spirally lengthwise.

2. An engine silencer comprising a pipe 70 connected with the exhaust of an internal engine and having a strip, the strip having tongues bent alternately to opposite sides of the strip and located the length of the pipe, the strip bent spirally lengthwise substantially 75 90° from one end of the strip to the other.

3. An engine silencer comprising a pipe, 80 a strip having substantially semi-elliptical tongues cut therefrom and bent alternately to opposite sides thereof and so as to fit the walls of the pipe, a lens shaped drum secured to the end of the pipe and having an exhaust port.

4. An engine silencer comprising a pipe, 85 a strip having semi-elliptical tongues cut therefrom and bent alternately to opposite sides thereof and so as to fit the walls of the pipe, a lens shaped drum secured to the end 90 of the pipe and having an elliptical exhaust port, a short pipe terminating in a circular opening covering the said elliptical opening of the said drum.

5. An engine silencer comprising a pipe 95 connected with the exhaust of an internal combustion engine, and having a strip extending lengthwise of and diametrically across the pipe, and dividing the pipe into semi-cylindrical chambers, the strip having tongues bent alternately to opposite sides of the strip, and having passage-ways for exhaust gases back and forth through the strip.

6. An engine silencer, comprising a pipe, 105 a strip having tongues cut therefrom and bent alternately to opposite sides thereof to baffle exhaust gases as they pass through the pipe, and to direct them through the openings formed by cutting and bending the tongues from the strip.

7. An engine silencer, comprising a pipe 110 connected with the exhaust of an internal combustion engine, and having a strip dividing the pipe into two semi-cylindrical chambers, tongues extending angularly from the pipe and dividing the semi-cylindrical chambers into a plurality of shorter chambers, the strip having openings to allow exhaust gases to pass alternately through the short chambers on opposite sides of the strip.

8. An engine silencer, comprising a pipe 115 120 connected to the exhaust of an internal combustion engine, the pipe having a central wall and a plurality of transverse walls, forming a plurality of short chambers extending along the central wall, the central walls having openings forming communicating passage-ways to the shorter chambers on opposite sides of the pipe, and forming a 125 sinuous communicating passage-way through the pipe back and forth along opposite sides 130

of the strip from one end of the pipe to the other.

9. An engine silencer, comprising a pipe connected to the exhaust of an internal combustion engine, a central strip located in the pipe and dividing the pipe into two semi-cylindrical chambers, tongues cut from the strip and bent so as to extend alternately from opposite sides of the strip, the edges 10 of the tongues fitting the wall of the pipe, the openings formed by cutting and bending

the tongues from the strip being located at the side of the tongues toward the inlet end of the pipe for permitting exhaust gases to pass along the short chambers to the tongues 15 and be directed to opposite sides of the strip from the inlet end to the outlet end of the pipe.

In testimony whereof, I have hereunto signed my name to this specification.

JOHN A. MAYER.
